UNITED STATES PATENT OFFICE

2,541,527

BRUSH SHUNT PROTECTOR

Erle Martin, West Hartford, Conn., assignor to
 United Aircraft Corporation, East Hartford,
 Conn., a corporation of Delaware

Application November 3, 1947, Serial No. 783,654

6 Claims. (Cl. 191—1)

1

This application relates to brushes for conducting electricity between relatively rotating elements, and particularly to the shunt connecting the brush with a contact member.

An object of this invention is an electrical brush of an improved and more durable construction.

A further object is to prolong the life of the brush shunt.

A still further object of this invention is a protected brush shunt.

Other objects and advantages will be apparent from the specification and claims, and from the accompanying drawings which illustrate what is now considered to be a preferred embodiment of the invention.

Fig. 1 is a side elevation, with portions in section, of a multiple brush holder.

Fig. 2 is a detailed enlarged elevation, with portions in section, showing the details of the improved brush construction.

The brush forming the subject of this application may have many uses but finds particular utility in transmitting electricity from the nose of the engine to the hub of an aeronautical propeller, for the purpose of conducting electricity to the blade heating means. This electricity is used to heat selected portions of the blade to prevent the formation of ice thereon or to remove ice that may have formed. Aeronautical propellers are subject to severe vibration and it has been found in practice that the flexible shunt connecting the brush with the contact member failed after a very short period, such as ten hours of running, this failure taking place most frequently near either the brush itself or the contact member where the shunt was supported and restrained and hence, somewhat less flexible than in the intermediate portion.

Applicant has found that by supporting the shunt within a casing of sponge rubber he is able to prolong the life of the shunt to several hundred hours instead of the ten hours mentioned above. In the embodiment shown, the brush member 10, which may be of carbon or any other suitable material, rigidly supports the shunt 12, by means conventional to the brush manufacturing art, thus giving one end of the shunt a firm support in the brush 10. Shunt 12 may comprise a plurality of small wires of copper or other suitable material twisted, braided or woven into a flexible assembly. The opposite end of the shunt may pass through and be supported in, a contact member 14 which may be of silver plated copper or any other suitable material. The shunt 12 may be soldered in position in contact member 14 after

2

being splayed out in countersunk portion 16 of contact member 14. A compression spring 18 extends between brush 10 and contact member 14 and tends to keep shunt 12 under tension. The spring 18 is guided on brush 10 by a pilot 20 and on cap 16 by a pilot 22.

A sponge rubber casing indicated generally at 23 surrounds shunt 12 and fills the space between the shunt and spring 18, thus supporting the shunt in a central position within the spring. The sponge rubber may be of two densities to better support the shunt. Rubber of a heavy density may be placed close to the contact member, as at 25, and close to the brush, as at 28, to help support the restrained portions of the shunt. The sponge rubber 24 between these two dense portions may be of a less dense and more flexible nature to permit flexing of the shunt when the spring and rubber are compressed as when the brush is in operating position.

Brush 10 may be hexagonal in shape to fit a hexagonal brush holder but the contact member may be cylindrical.

In order to support the brushes in operative position, a brush holder, indicated generally at 30, is supported on a frame 32 which may be removably secured to the engine nose. Bolts 34 pass through a block of insulating material 36 forming a portion of the brush holder 30 and through frame 32 to secure the brush holder in position on frame member 32. A bus bar 38 is secured in position on the insulating material 36 and at one end carries means for connecting the bus bar with a source of electricity, indicated in the drawings as a wire 40.

Insulating material 36 supports a plurality of brush holders comprising hollow cylindrical sleeves 42 radiating from a common center concentric with slip ring 44 mounted on the inboard end of a propeller hub and rotatable therewith. Hollow sleeves 42 may be hexagonal on the interior so as to fit and guide brush 10. The brush assembly shown in Fig. 2 is inserted through the open end of the sleeve 42 so that cylindrical contact member 14 slides within the hexagonal hole. A rubber ring member 46 is received in a groove in contact member 14 and provides sufficient friction between contact member 14 and sleeve 42 to retain the brush assembly in the sleeve 42 after the brush is assembled with the sleeve.

It is apparent that insertion of the brush assembly into the hollow sleeve will force the contact member 14 into contact with the bus bar 38 and will compress spring 18, and sponge rubber

24. This compressed spring and rubber act to urge contact member 14 into contact with bus bar 38 and to urge brush 16 outwardly into contact with slip ring 44.

In the manufacture of the brush assembly shown in Fig. 2, shunt 12 is permanently attached to brush 16 and spring 18 is then assembled over shunt 12. The opposite end of shunt 12 is passed through, and soldered onto, cap 14. Uncured sponge rubber is cut in strips and wrapped around shunt 12 between the coils of spring 18. Ribbons of dense rubber having a blow ratio of about 1:2½ being used at the opposite ends of the shunt and less dense rubber having a blow ratio of about 1:5 being used in the intermediate portion. A mold fitting the outside of the spring convolutions is placed around the above described assembly and the entire assembly is subjected to heat. The rubber has been impregnated so that the heat will cause it to expand, or blow, substantially filling the mold and forming the sponge rubber. This mold may then be removed and the brush is ready for use. The heat vulcanizes the sponge rubber into a single complete sleeve, vulcanizing the parts of different densities together. There is some tendency to vulcanize the rubber sleeve to the shunt and the contact member but such vulcanization is not essential.

The completed spring and sponge rubber assembly should have a diameter sufficiently small so that the compression incident to assembly will not enlarge it sufficiently to bind in the brush holder sleeve 42.

The rubber casing acts to prevent the brush shunt from bending sideways sufficiently to chafe on the springs and also prevents the shunt from vibrating and causing fatigue failures, particularly near the restrained end portions of the shunt.

In addition, the rubber acts as a form of damper which will prevent the brush from chattering due to the vibration.

It is to be understood that the invention is not limited to the specific embodiment herein illustrated and described, but may be used in other ways without departure from its spirit as defined by the following claims.

I claim:

1. In combination with a brush, a contact member, a flexible shunt connected at one end with said brush and at the other end with said contact member, and a compression spring between said brush and contact member and surrounding said shunt; a sponge rubber casing surrounding said shunt and substantially filling the space between said shunt and said spring and extending from said brush to said contact member.

2. In combination with a brush, a contact member, a brush shunt, connected at one end with said brush and at the other end with said contact member, and a compression spring between said brush and contact member and surrounding said shunt; a cellular rubber-like casing surrounding said shunt and substantially filling the space between said shunt and said spring and extending between said brush and said contact member.

3. In combination with a brush, a contact

member, a flexible shunt secured at one end to said brush and at the other end to said contact member, said flexible member being restrained adjacent said brush and said contact member by its attachment thereto, and a compression spring surrounding said shunt; means for protecting said shunt from damaging vibrations comprising a relatively dense sponge rubber casing surrounding the restrained portion of said shunt and substantially filling the space between said shunt and said spring and a relatively less dense sponge rubber casing surrounding said shunt and extending between and vulcanized to said relatively dense casings and substantially filling the space between said shunt and said spring.

4. In combination with a brush, adapted to fit and slide within a brush holder, a contact member adapted to slide within said brush holder, and a flexible shunt secured at one end to said brush and at the other end to said contact member; means for protecting said shunt from damaging vibrations comprising a sponge rubber casing surrounding said shunt and extending

between said brush and said contact member and having an outside diameter smaller than, but substantially as large as the brush or the contact member so as to slide within but not bind in said brush holder.

5. In combination with a brush, adapted to fit and slide within a brush holder, a contact member adapted to slide within said brush holder, and a flexible shunt secured at one end to said brush and at the other end to said contact member, said flexible member being restrained adjacent said brush and said contact member by its attachment thereto; comprising a relatively dense sponge rubber casing surrounding the restrained portion of said shunt and a

relatively less dense sponge rubber casing surrounding said shunt and extending between and vulcanized to said relatively dense casing and having an outside diameter smaller than but substantially as large as the brush or the contact member so as to slide within but not bind in said brush holder.

6. In combination with a brush, a contact member, a flexible shunt connecting said brush and said contact member and a compression spring surrounding said shunt and extending between said brush and contact member; shunt supporting means comprising a non-metallic resilient tube encasing and supporting said shunt and substantially filling the space between said shunt and said spring and extending between said brush and said contact member.

ERLE MARTIN.
